UNITED STATES PATENT OFFICE.

NATHAN W. CRANDALL, OF HARTFORD, CONNECTICUT, ASSIGNOR TO THE PERKINS CORPORATION, OF HARTFORD, CONNECTICUT, A CORPORATION OF CONNECTICUT.

FOUR-WAY SNAP-SWITCH.

No. 851,654.

Specification of Letters Patent.

Patented April 30, 1907.

Application filed July 27, 1906. Serial No. 328,118.

To all whom it may concern.

Be it known that I, NATHAN W. CRANDALL, a citizen of the United States, residing at Hartford, in the county of Hartford and 5 State of Connecticut, have invented a new and useful Four-Way Snap-Switch, of which the following is a specification.

This invention relates to the construction of a push button snap switch of the species 10 commonly known as a 4-way switch. These switches are used in connection with two 3-way switches for controlling a group of lights from any one of three localities. If additional localities of control are desired 15 4-way switches are joined so the lights can be controlled by any one of the switches. In 4-way switches according to their condition and the condition of the other switches in the circuit the current follows one of four different paths.

The object of this invention is to provide a very simple construction whereby a common push button switch mechanism may be easily transformed into an efficient 4-way switch, 25 thereby simplifying the production and cheapening the cost of a 4-way switch.

The specific construction of the pole-throwing mechanism of this switch is immaterial to this invention and many of the ordinary forms of mechanism could be utilized.

The feature of novelty in the invention resides in the arrangement and co-action of the stationary contacts and movable pole pieces whereby the terminals are either connected 35 across the ends through the contacts only or across the sides through some of the contacts and the poles.

In the form of invention illustrated in the drawings when the switch mechanism is actuated in such manner as to throw the movable poles out of engagement with the stationary contacts the line terminals at each end of the receptacle are connected with each other through the stationary contacts, and 45 when the switch mechanism is actuated so that the pole pieces engage the stationary contacts, the line terminals on each side are connected through the pole pieces and those across each end disconnected by reason of 50 a separation of the stationary contacts.

The type of push button switch actuating mechanism which is illustrated as most convenient for the purpose of explaining this in-

vention is that described in United States Patent No. 732,890, dated July 7, 1903.

Figure 1 of the accompanying drawings shows a side elevation of one of these switches constructed according to this invention, with the side of the receptacle cut away so as to expose the mechanism, the parts being in the 55 positions occupied when the movable pole pieces are engaged with the stationary contacts so as to connect the side terminals. Fig. 2 shows the push buttons, the spring plate to which they are connected, the escape 60 plate to which the pole pieces are adapted to be connected and the oscillating escapement in the same relative positions as shown in Fig. 1. Fig. 3 shows the same parts with the push buttons in the positions occupied just 65 before the escapement is released to allow the pole pieces to be thrown for disengaging them from the stationary contacts. Fig. 4 shows the same parts in the positions occupied 70 before the escapement has been oscillated 75 so as to allow the pole pieces to be thrown for disengaging them from the stationary contacts. Fig. 5 shows an enlarged transverse section of the mechanism taken through the frame plate on the plane of the spindle. Fig. 6 shows a horizontal section of the receptacle. Fig. 7 shows the metal part of one of the pole pieces. Fig. 8 shows the insulation part of one of the pole pieces. Fig. 9 shows the diagram of a manner of connecting up one 85 of these switches. Fig. 10 is a vertical transverse section of the receptacle showing the stationary spring contact fingers at one end 90 in contact, as they are when not separated by the movable pole pieces.

The receptacle 1 for this switch may be made of porcelain or any other suitable material in any desired shape. The stationary contacts are preferably spring fingers arranged in pairs at each end and fastened in 95 the interior to the bottom of the receptacle. The outer contact fingers 2 of each pair are preferably connected with plates 3 that at their upper ends have binding screws 4 for the attachment of the ends of the line wires. 100 The inner contact fingers 5 at each end are joined or formed from a single piece and they are so bent that they spring against and tend to make close contact with the adjacent outer contact fingers when they are in their 105 normal positions and are not separated by

the pole pieces. As a result of this construction when the pole pieces are not between the pairs of spring fingers so as to separate them the line wire terminals are connected 5 across each end of the switch through the stationary spring finger contacts.

The spindle 6 of the form of mechanism illustrated extends loosely through the hub 7 of the frame plate 8 which is attached to 10 the supporting plate 9 that is secured across the open end of the receptacle. A face plate 10 is attached by screws to the supporting plate in the usual manner.

The pole pieces are mounted upon the 15 ends of the spindle. Each pole piece consists of an outer metallic plate 11 and an inner insulating plate 12. The ends of these pole plates are adapted to be thrown between or withdrawn from between the 20 spring fingers which form the stationary contacts by the actuating mechanism. When the pole pieces are between the stationary contacts the outer fingers of the stationary contacts on each side are electrically connected through the metallic pole 25 plates, and the inner fingers of the stationary contacts are electrically separated from each other and from the adjacent outer fingers by the insulating plates of the pole pieces. 30 When the pole pieces are withdrawn from between the stationary contacts there is no metallic connection between the outer fingers on each side but there is instantly formed metallic connection between the outer fingers 35 at each end through the adjacent inner fingers.

The spring plate 13 has a hub 14 which is loosely mounted on the frame plate hub. Pivotedly connected with opposite sides of 40 the spring plate are the shanks 15 of the push button 16.

Loosely mounted on the spindle is an escape plate 17. This plate is connected with one pole piece by a lug 18 and with the other 45 pole piece by a lug 19 so that its oscillation causes the oscillation of the pole pieces. The lug 18 extends from the escape plate toward the spring plate and the spring plate has a lug 20 that extends toward the escape 50 plate. A spring 21 is coiled about the hub of the spring plate in such manner that its ends extend against opposite edges of both of the lugs 18 and 20.

On the edge of the escape plate are two 55 teeth 22 and pivotally mounted on a stud 23 that projects from the frame plate, so that its ends will engage these teeth is the escape yoke 24. A spring 25 extends across and is fastened to the ends of the yoke in position 60 to engage lugs 26 that project rearwardly from the escape plate teeth.

When the outer of the push buttons is thrust inwardly the spring plate is oscillated and the coiled spring put under tension. 65 The escape yoke holds the escape plate from

turning and consequently holds the poles from being thrown until the push button is pushed in far enough to engage the end of the escape yoke in such manner that further movement of the push button disengages the 70 other end of the escape yoke from a tooth of the escape plate and allows the escape plate and the poles to be thrown by the spring which at this time is under sufficient tension to throw the poles violently. 75

When the actuating mechanism is operated and the poles of this switch are thrown so as to engage the contacts and connect the terminals on each side, current can pass through the switch in either direction across 80 either side. When the pole pieces are thrown so that they do not connect the contacts current can pass in either direction across either end of the switch through the spring contact fingers. 85

When a 4-way switch embodying this invention is connected up with two 3-way switches, as illustrated in Fig. 9, a group of lights, or other electrical apparatus, 27, may be turned on or off from the locality of either 90 of these three switches.

If the pole pieces of the 4-way switch embodying this invention are thrown so that they do not connect the side contacts and it is desired to light the lamps from the locality 95 of switch 28 that switch is operated and then the current will flow in the circuit from the plus main to the terminal 30, then through the pole of this switch to the terminal 31, then to the end terminal 32 of the 4-way switch, then to the end terminal 33, and from there to the terminal 34 of the 3-way switch 29 and through the pole of that switch to the terminal 35, and to the lamps and the minus main. This circuit can be 105 opened by pushing either of the switches. If the switch 28 is pushed terminal 30 is disconnected from terminal 31. If the switch 29 is pushed terminal 34 is disconnected from terminal 35. If the 4-way switch is 110 pushed terminal 32 is disconnected from terminal 33. If the lights are put out by pushing the switch 28 and disconnecting the terminal 30 from the terminal 31, then the terminal 36 is connected with the terminal 37, 115 as usual with a 3-way switch. With this construction made the lamps can be lighted by pushing the switch 28 and again connecting 30 and 31, or by pushing the switch 29 and connecting 40 and 41, in which case the 120 current passes through the 4-way switch from the terminal 38 to the terminal 39, or by pushing the 4-way and connecting the terminals 38 and 33. If the lamp circuit was opened by pushing the 4-way switch instead 125 of either of the 3-way switches, then 32 would not be connected with 33 nor 38 with 39, but 32 would be connected with 39 and 33 with 38 through the poles of the 4-way switch. Then the lamps could be light by 130

snapping the 4-way switch so that the end terminals would be connected, or by pushing the switch 28, in which case the current would flow through the 4-way switch from 38 to 33 and thence to the lamps, or by pushing the switch 29 in which case the current would flow through the 4-way switch from 32 to 39 and thence to the lamps.

5 The invention claimed is:—

- 10 An electrical snap switch having four pairs of stationary spring contacts, said contacts being arranged to engage with one another in pairs, a pair of oscillating poles that are insulated from each other, each pole being

formed of conducting material and insulating material and arranged to be thrown between pairs of stationary contacts and when in such position to insulate the contacts that were in engagement and electrically join the contacts that were separated, 15 mechanism for throwing the poles, and push buttons for actuating said mechanism, substantially as specified.

NATHAN W. CRANDALL.
